UNITED STATES PATENT OFFICE.

FREDERICK A. LIND, OF TURTLE CREEK, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed May 6, 1919. Serial No. 295,069.

To all whom it may concern:

Be it known that I, FREDERICK A. LIND, a citizen of the United States, and a resident of Turtle Creek, in the county of Allegheny and State of Pennsylvania, have invented a new and useful Improvement in Lightning Arresters, of which the following is a specification.

My invention relates to lightning arresters and it has particular relation to arresters of the type usually known as "multi-path" arresters and comprising two electrodes spaced apart by means of a discharge block composed of particles of conducting and non-conducting materials.

The object of my invention is to provide an arrester of the character designated wherein any discharge of current through the block caused by voltage slightly above normal in the circuit to which it is attached will be allowed to pass to ground without, in any way, affecting the arrester and wherein any excessive discharge of current caused by a very high potential being impressed on the circuit will automatically increase the resistance thereof to a point which will render a continuous flow of current through the established path impossible and thereby cause the current to seek a new path, provided the voltage is still above normal.

Heretofore, it has been suggested to use a discharge block composed of a mixture of lead peroxid and some insulating or some conducting granules which serve to either decrease or increase the resistance of the discharge block, this block being separated from the spaced electrodes by means of insulating films thereon. One objection to this type of arrester is that, when a potential surge occurs on the line, whether of relatively great or relatively small value, the insulating films will be punctured and, due to the low resistance of the lead peroxid, an excessive current will flow to ground, heating the lead peroxid and permanently changing its resistance to a much greater value so that even a very slight increase in potential on the line will render a portion of the discharge block permanently useless as a protection against surges of the voltage for which it was designed.

By my invention, I provide an arrester in which the discharge block composed of lead peroxid and either conducting or insulating material is replaced by a similar block

formed of a mixture of particles of conducting, insulating and lead peroxid particles. Such a block may comprise particles of carbon and of lead peroxid separated by any suitable insulating compound. The insulating particles serve to hold the conducting and lead peroxid particles in invariable but spaced relation with respect to each other, thereby eliminating the necessity of the insulating film and improving the protection afforded by the arrester.

In the single figure of the accompanying drawing, which is a sectional view of my arrester, I show two conducting plates 1 and 2 which are connected to a supply line 3 and to ground, 4, respectively, and are spaced apart by means of a discharge block 5 composed of intermingled particles of conducting and non-conducting material and lead peroxid. The non-conducting material serves as a binder and also serves to insulate the conducting and lead peroxid particles.

In an arrester of this type, any small discharge of current of short duration will pass through the block to ground without producing any appreciable increase in the temperature thereof on account of the cooling effect of the discharge block. However, should a small continuous current or a large current of any duration pass through the block, it will be heated thereby and the lead peroxid in the particular path followed by the current will be changed to a lower oxid of relatively great resistance, thus either choking off the current, or, if it is of sufficiently high potential, causing it to seek another path of discharge. This same effect will tend to seal any imperfection in the discharge block due to alinement of conducting particles and will thereby restore it to its originally intended discharge-voltage breakdown.

One of the inherent properties of a discharge block composed of spaced particles of conducting material is that conductance thereof is substantially nil at the potential of the circuit which it is designed to protect and that any increase in potential thereof results in a decrease of resistance at an even greater rate than the potential rises. This property causes relatively insignificant current to pass through the block at normal voltage of the circuit and causes a very large current to pass therethrough when excessive potentials are impressed thereon. On the other hand, the property of the lead peroxid,

that is, having a relatively insignificant resistance to a small current and having a relatively great resistance to a larger current, caused by the change therein resulting from the heat generated by the large current, causes this material to co-operate with the intermingled particles of conducting and non-conducting material to allow a relatively small current to pass therethrough without 10 in any way affecting the composition of the discharge block, whereas, a relatively great increase in potential causes a relatively large current to pass through the block immediately raising its temperature and changing 15 the lead peroxid into a lower oxid of relatively great resistance, thereby choking off the discharge passing therethrough or causing it to seek a new path.

While I have shown but one form of my 20 invention and described in detail only one embodiment thereof, it will be understood by those skilled in the art that it is not so limited but is susceptible of various minor changes and modifications without departing 25 from the spirit thereof and I desire, therefore, that only such limitations shall be placed thereupon as are imposed by the prior art or are specifically set forth in the appended claims.

30 I claim as my invention:

1. An electrical-discharge device comprising a plurality of spaced conducting members, and means disposed intermediate said members embodying intermingled particles of conducting material, non-conducting material, and a metal compound which becomes converted by heat into a compound of high resistance.

2. An electrical-discharge device comprising a plurality of spaced conducting members, and means disposed intermediate said members embodying intermingled particles of conducting material, non-conducting material, and a conductive oxid which becomes converted by heat into a different oxid of higher electrical resistance.

3. An electrical-discharge device comprising a plurality of spaced conducting members, and means disposed intermediate said members embodying intermingled particles of conducting material, non-conducting material, and a metal compound of low heat conductivity and low electrical resistance which becomes converted by heat into a compound of different chemical composition and higher electrical resistance.

4. An electrical-discharge device comprising a plurality of spaced conducting members, and means disposed intermediate said members embodying intermingled particles of conducting material, non-conducting material, and lead peroxid.

5. An electrical-discharge device comprising a plurality of spaced conducting members, and means disposed intermediate

70 said members embodying intermingled particles of conducting material, non-conducting material, and lead peroxid, said particles being held in an invariable but spaced relation.

6. An electrical-discharge device comprising a plurality of spaced conducting members, and means disposed intermediate said members embodying intermingled particles of conducting material, non-conducting material, and a lead peroxid, said conducting and lead peroxid particles being held in invariable but spaced relation by means of 75 said non-conducting particles.

7. A lightning arrester comprising two 80 spaced conducting plates, one of which is connected to a source of supply and the other of which is connected to ground, and means disposed intermediate said plates embodying intermingled particles of conducting material, non-conducting material, and lead peroxid, said particles of conducting material and of lead peroxid being held in invariable but spaced relation by means of 85 the insulating material.

8. A lightning arrester comprising two 90 conducting electrodes, one of which is connected to a supply circuit and the other of which is connected to ground, and a discharge block disposed intermediate said 95 electrodes and comprising a plurality of current paths the conductance of which varies in direct relation to the potential of said circuit and in inverse relation to the current passing through said arrester.

9. A lightning arrester comprising two 100 conducting electrodes one of which is connected to a supply circuit and the other of which is connected to ground, and a discharge block disposed intermediate said electrodes 105 and comprising a plurality of current paths the conductance of which is substantially nil when normal potential is impressed on said supply circuit and which varies in direct relation to potential thereof and in inverse relation to the current passing through 110 said arrester.

10. A lightning arrester comprising two 115 conducting electrodes one of which is connected to a supply circuit and the other of which is connected to ground, and a discharge block disposed intermediate said electrodes, the conductance of which varies in direct relation to the potential of said circuit and in inverse relation to the current 120 passing through said arrester.

11. A lightning arrester comprising two 125 conducting electrodes one of which is connected to a supply circuit and the other of which is connected to ground and a discharge block disposed intermediate said electrodes, the conductance of which is substantially nil when normal potential is impressed on said supply circuit and which varies in direct relation to the potential 130

- thereof and in inverse relation to the current passing through said arrester.
12. A lightning arrester comprising two conducting electrodes one of which is connected to a supply circuit and the other of which is connected to ground, and a discharge block disposed intermediate said electrodes and embodying a mixture of two materials, the conductance of one of which varies in direct relation with the potential of said circuit and the conductance of the other of which varies in inverse relation with the current passing through said arrester.
13. A lightning arrester comprising two conducting electrodes one of which is connected to a supply circuit and the other of which is connected to ground and a discharge block disposed intermediate said electrodes and embodying a mixture of two materials, the conductance of one of which is substantially nil when normal potential is impressed on said circuit and which varies in direct relation with the potential of said circuits, and the resistivity of the other of said materials being substantially nil when relatively small currents pass through said discharge block and which varies in direct relation with current passing therethrough.
14. An electrical-discharge device comprising a plurality of spaced conducting members, means disposed intermediate said members the impedance of which varies inversely with the difference of potential between said members, and additional means disposed throughout the major portion of the space between said members, the resistivity of which varies with the temperature thereof.

15. An electrical-discharge device comprising a plurality of spaced conducting members, means disposed intermediate said members the impedance of which becomes materially reduced when the potential difference between conducting members exceeds a critical value, and additional means combined with said first named means whereby the resistivity of said block is caused to vary with temperature thereof.

16. An electrical-discharge device comprising a plurality of conducting members having a space therebetween, means disposed intermediate said members the impedance of which becomes materially reduced when the potential difference between conducting members exceeds a critical value, and additional means disposed throughout the major portion of the space intermediate said conducting members and adapted to seal any current path through said space upon the heating thereof.

17. An electrical-discharge device comprising a plurality of conducting members having a space therebetween, means disposed intermediate said members the impedance of which becomes materially reduced when the potential difference between conducting members exceeds a critical value, and additional means disposed throughout the major portion of the space intermediate said conducting members and adapted to seal any current path through said space upon the continuous passage of current therethrough.

In testimony whereof, I have hereunto subscribed my name this 23rd day of April 1919.

FREDERICK A. LIND.
